HYDROCARBON RECONSTRUCTION

Filed Jan. 13, 1942

UNITED STATES PATENT OFFICE

2,403,649

HYDROCARBON RECONSTRUCTION

Frederick E. Frey, Bartlesville, Okla., assignor to
Phillips Petroleum Company, a corporation of
Delaware

Application January 13, 1942, Serial No. 426,627

18 Claims. (Cl. 260—683.5)

1

This invention relates to the conversion of hydrocarbons. More particularly, it relates to chemical reconstruction of hydrocarbons in the presence of hydrofluoric acid as a catalyst. This application is a continuation in part of my co-pending application Serial No. 323,443, filed March 11, 1940, now Patent 2,317,901, issued April 27, 1943.

I have discovered that, in the presence of substantial proportions of hydrofluoric acid and under suitable conditions of time and/or temperature, hydrocarbons can be catalytically reconstructed to hydrocarbons of different carbon-skeleton arrangement and/or different boiling point, thereby effecting an improvement in properties and in usefulness for specific purposes. Paraffinic hydrocarbons boiling in the motor-fuel range, for example, undergo conversion to isomers and to hydrocarbons of both lower and higher molecular weights and correspondingly lower and higher boiling temperatures. Similarly, motor-fuel fractions containing minor proportions of unsaturates are converted into completely saturated materials containing some lower-and higher-boiling products. Accordingly, the present invention comprises subjecting hydrocarbon material consisting predominantly of saturated hydrocarbons to the action of a substantial proportion of concentrated hydrofluoric acid at a suitable reaction temperature and pressure and for a time sufficient to effect the desired extent of conversion. Recycling of unreacted hydrocarbons and/or of selected fractions of the product may be practiced. By the term "saturated," I intend to exclude unsaturated hydrocarbons such as olefins, diolefins, acetylenes, and the like.

In general, this invention may be used to convert or improve hydrocarbon materials comprising substantially entirely saturated hydrocarbons; although minor proportions of unsaturated hydrocarbons initially present can be tolerated, it is not intended that my invention shall include a process only for the alkylation of saturated hydrocarbons by reaction with unsaturated hydrocarbons. The specific effect produced in any particular case is usually one or more of the following: (1) increased octane number of motor-fuel range hydrocarbon materials; (2) enhanced susceptibility to antiknock improvement by the addition of tetraethyl lead to hydrocarbon materials; (3) conversion of hydrocarbons to hydrocarbons of higher and/or lower molecular weights; (4) decreased content of unsaturates in hydrocarbon materials; (5) conversion of hydrocarbons to relatively highly branched isomeric

compounds; (6) conversion of noncyclic hydrocarbons to cyclic compounds. When the initial material has a considerable proportion of naphthenes, disproportionation of these to paraffins and aromatics appears to occur, especially at relatively drastic conditions of time and temperature.

The production of these effects indicates that several different types of chemical reactions may be involved in the present process for reconstruction of hydrocarbons. The predominating reaction types, as deduced from a consideration of reactants, products, operating conditions, and theoretical aspects relating to the invention, may be exemplified as follows:

The first two reactions, namely, reconstruction to produce both higher-and lower-boiling paraffins, and isomerization, respectively, predominate under relatively mild treating conditions. The yields of cycloids, exemplified in the third equation by cyclohexane, is increased by increasing the temperature and/or the time of reaction. A fourth type of reaction is believed to account for the increase in saturation and stability that occurs when motor fuel comprising some unsaturated material is treated. By this reaction, olefins are converted to cycloparaffins such as cyclohexane and its derivatives. This reaction may be exemplified as follows:

Several other types of reactions undoubtedly occur in the reconstruction process; however, the above-mentioned five types appear to account for most of the effects which are produced. The general term "reconstruction" is used herein to denote the production of one or more of the above-mentioned effects and/or of other inherent ad-

vantageous effects which result from the practice of my invention.

Insofar as I have been able to determine, the actual catalyst which promotes the reconstruction reaction, or reactions, is concentrated hydrofluoric acid. Other materials may be present which will exert a slight promoting effect, such as compounds fortuitously formed in minor amounts by reaction of hydrofluoric acid with walls of reaction vessels, but the presence of such compounds does not alter the fact that hydrofluoric acid is the catalyst. Agents which promote the action of the hydrofluoric acid may be added in many instances without changing the character of the reaction nor exceeding the scope of the spirit of the invention and of the disclosure. The reaction may take place in the presence of relatively or essentially inert solids of large surface area such as activated charcoal, bauxite, etc. which will tend to adsorb and concentrate hydrofluoric acid in an active state. When it is desired to maintain hydrofluoric acid in a liquid phase at higher reaction temperatures, this effect may be aided by incorporating with the hydrofluoric acid inorganic salts which are soluble in hydrofluoric acid, especially the fluorides of alkaline materials and of alkali-earth metals.

An object of this invention is to provide a new process for catalytically reconstructing hydrocarbon material.

A further object is to produce hydrocarbons of lower and/or higher molecular weight and of correspondingly lower and/or higher boiling points than those of the material treated.

A specific object is to treat motor fuel so as to enhance its susceptibility to improvement of its antiknock rating by the addition of tetraethyl lead.

Another specific object is the production of saturated hydrocarbons boiling in the motor-fuel range and having increased unleaded and leaded octane numbers as compared with the original material or corresponding fractions thereof.

Another specific object is to improve hydrocarbons, such as those obtained by petroleum refinery operations, and especially those boiling in the motor-fuel range, by increasing the degree of saturation and, consequently, the stability, when a small but undesirable proportion of unsaturates are originally present.

Another specific object is to convert normal or slightly branched aliphatic hydrocarbons to more highly branched aliphatic hydrocarbons.

A further object is to convert normal paraffins into corresponding isoparaffins.

Other objects and advantages of my invention will be apparent from the accompanying disclosure and discussion.

An understanding of some of the many aspects of the invention may be aided by the accompanying drawing, which is a flow-diagram illustrating a preferred arrangement for practicing the invention.

A suitable hydrocarbon material, admitted to the system through inlet 10, pump 11, and valve 12, is mixed in conduit 13 with concentrated, preferably anhydrous, hydrofluoric acid, which is admitted through inlet 14, pump 15, and valve 16. The proportion of hydrofluoric acid is preferably in the range from 0.2 to 4 times by weight of the total hydrocarbon fluids. Proportions much smaller than this are sometimes insufficient to effect the desired degree of conversion, whereas much larger proportions decrease undesirably the

production capacity of equipment of any given size; however, proportions outside of the preferred range should not be excluded from the scope of this invention. Mixing of the hydrofluoric acid and the hydrocarbon material may be effected by any of a number of methods, as by the use of a special mixer or emulsifier, or by maintaining high linear velocities in conduit 13; devices such as sharp bends or constrictions in conduit 13 are advantageous in some instances.

The resulting mixture is passed to heater 17, wherein it is heated to a suitable reaction temperature. Heater 17 preferably consists of a tube coil surrounded by hot gases or liquids. In some instances, as when the desired reaction temperature is atmospheric, or only slightly above, heater 17 is unnecessary and may be by-passed or removed from the system.

Depending somewhat upon the character of the initial hydrocarbon material, the reaction temperature may vary from about 50 to about 1000° F.; a temperature in the range of 250 to 800° F. is usually preferred. The pressure may vary from about atmospheric to 5000 pounds per square inch, or more. The reaction time may vary from about one minute to twenty hours or more, high values applying to relatively low reaction temperatures or to highly refractory reactants, and low values applying to relatively high operating temperatures or to highly reactive reactants. Depending upon the particular hydrocarbon material being treated and upon the region of temperature and pressure under which the reconstructing reaction is conducted, the mixture of hydrocarbons and catalyst may be in a wholly gaseous phase, in a partially liquefied condition, or in a virtually wholly condensed condition. The extent of conversion increases with increase in temperature, time, and/or catalyst concentration. Changes in pressure appear to affect the nature of the reaction appreciably, particularly at high temperatures. In general, an increase in pressure retards the formation of lower-boiling hydrocarbons and increases the formation of higher-boiling hydrocarbons; also, increase in pressure tends to increase the rate of conversion, particularly under gas-phase operating conditions. Over-reacting may lead to the formation of some heavy oils, usually of relatively low value, and of some organic fluorine-containing compounds of high molecular weight, which usually remain mostly dissolved in the hydrofluoric acid when the proportion of acid is large enough for a separate liquid acid phase to be produced upon cooling the reaction mixture.

The optimum operating conditions in any specific case are dependent upon the nature of the feed material as well as upon the extent of reconstruction desired. For example, in treating a lube oil to decrease unsaturation or to modify such properties as the pour point, the viscosity, or the like, relatively mild reconstructing conditions are used. By contrast, in reconstructing relatively refractory materials, such as normal butane or normal pentane, to produce isomers and higher-and/or lower-boiling hydrocarbons, relatively drastic conditions are required. For reconstructing normal butane to produce isobutane, the preferred conditions are a temperature in the range of 400 to 800° F., a pressure in the range of 250 to 2500 pounds per square inch, and a reaction time in the range of 1 to 100 minutes; but conditions outside of these ranges may at times be used, in accordance with the principles of the invention. The reconstructing reactions to im-

prove the antiknock characteristics of motor-fuel hydrocarbons are usually carried out under somewhat less drastic conditions than those preferred for the reconstruction of normal butane. For any particular case, the optimum conditions are readily determinable by trial by one skilled in the art in the light of the present disclosure and discussion.

When the requisite reaction time is relatively short, such as about one to about ten minutes, the reaction may be carried out preferably wholly in tube heater 17, from which the reaction mixture is conducted via pipe 18 and valve 19 directly to cooler and separator 20. When the requisite reaction time is relatively long, it is advantageous to pass the heated mixture from heater 17 through valve 21 and conduit 22 to reactor 23, wherein the mixture is digested at the reaction temperature and pressure for a time sufficient to effect the desired conversion. Such digestion may need to be accompanied by vigorous agitation when relatively immiscible liquid phases are present. When liquid-phase or mixed-phase operating conditions are used, means for effecting agitation or mixing in reactor 23 are usually desirable, because liquid hydrocarbon-hydrofluoric acid mixtures tend to separate into two layers. Mixing may be effected by any well-known means, such as mechanical stirrers, relatively constricted orifices or zones through which the mixture is passed at high linear velocity, or the like; it may be aided by recirculation, as through circuit 24, pump 25, and valves 26 and 27. If all components of the reaction mixture are in a single phase, no means of agitation will generally be required. Usually the heat of reaction is relatively small and does not markedly affect the temperature of the reacting mixture. Preferably, reactor 23 is operated adiabatically; but, if desired, auxiliary heating or cooling devices may be incorporated in reactor 23, although control of the temperature therein is more suitably effected by controlling the heat input in heater 17.

I have found that the solubility of saturated hydrocarbons in hydrogen fluoride, and the solubility of hydrogen fluoride in such hydrocarbons increases with elevation in temperature. At temperatures near but below the critical for hydrogen fluoride, under supercritical pressures I have found it convenient to operate with a liquid hydrogen fluoride phase containing a high content of dissolved hydrocarbon. In such instances agitating means are sometimes unnecessary, during the digestion period in which the reaction is effected, as discussed. Similarly, I may operate in the sub-critical temperature region with respect to a hydrocarbon phase carrying in solution a high proportion of hydrogen fluoride or acid. Reaction may be effected in acid rich liquid phase by contacting the hydrocarbon to be converted with liquid hydrogen fluoride at elevated temperature, thereafter separating the acid phase, now containing the reactant hydrocarbon in solution, and then subjecting the solution to reaction conditions. The acid rich effluent from such a step may be distilled to recover the volatilizable hydrocarbons together with a part of the acid, while the residue of hydrocarbon-depleted acid may be used again in the conversion step. In another modification hydrocarbon material may be introduced into the lower end of a column of liquid acid maintained at reaction temperature through which the hydrocarbon ascends by virtue of its lower density, undergoing as it ascends partition with the hydrocarbon dissolved in the

acid phase, wherein most of the reaction takes place. Converted hydrocarbon separates as an upper layer from the acid, from which it may be withdrawn. Acid passing out of solution on cooling may be allowed to return to the column of acid.

The effluent mixture from reactor 23 is passed through conduit 28 having valve 29 to separator 20 wherein it is separated into two liquid phases, 10 as by cooling and gravitation or centrifugal means. The lighter or hydrocarbon phase is passed through conduit 30 having valve 31 to fractionator 32. The heavier or hydrofluoric acid phase may be recycled via conduit 33 having valve 34 to pump 15; however, preferably at least 15 part of it is passed through valve 35 and conduit 36 to acid fractionator 37, wherein it is purified before being reused.

From fractionator 32 is passed a comparatively minor overhead fraction, which comprises free hydrogen fluoride and relatively low-boiling hydrocarbons, through valve 38 and conduit 39 to separator 40. The remaining or major portion of material, which comprises substantially pure hydrocarbons with very small proportions of organic fluorine compounds, is passed through valve 41 and conduit 42 to defluorinator or fluorine remover 43.

Fluorine remover 43 comprises a chamber containing a contact mass having hydrogenation and/or dehydrogenation properties, such as bauxite, alumina, or other similar material. Usually suitable operating conditions are a temperature in the range of 75 to 250° F. and a space velocity in the range of 1 to 50 volumes of liquid hydrocarbon material per volume of contact mass per hour. Under such conditions, which may be particularly selected in accordance with a trial, organically combined fluorine is substantially completely removed from the hydrocarbon material, which then is passed through valve 44 and conduit 45 to fractionator 46. Such defluorination is more completely disclosed, and is claimed, in my copending application Serial No. 398,361, filed June 16, 1941. This is now Patent 2,347,945, issued May 2, 1944. When organic fluorine compounds are not present or harmful, or are to be removed by treating only a part of the material present, the hydrocarbon material can be passed directly to fractionator 46, entirely or in part, from conduit 42 through conduit 69 and valve 10, valves 41 and 44 being partially or completely closed.

Fractionator 46 effects a separation of the hydrocarbon mixture into the desired products, by-products, and recycle fractions. For example, if the principal product is motor fuel, the following four fractions may be obtained: (1) a by-product fraction comprising chiefly isoparaffins boiling below the motor-fuel range, which is withdrawn through outlet 47 having valve 48, and which may be used as conversion stock in an alkylation process; (2) a motor-fuel fraction, which is withdrawn through outlet 49 having valve 50; (3) a fraction boiling above the motor-fuel range, which may be recycled by way of valve 51 and conduit 52 to pump 11; and (4) a bottom fraction comprising a high-boiling hydrocarbon residue, which may be withdrawn through outlet 53 having valve 54. If desired, the motor-fuel fraction withdrawn may be limited to a relatively narrow-boiling range in order to obtain relatively concentrated specific materials, such as, for example, highly-branched octanes, while other hydrocarbons boiling in the motor fuel range are

separately recovered, by means not shown or through 53, and/or passed to the conversion zone through conduit 52.

The overhead effluent from fractionator 32 is separated into two phases in separator 49, as by cooling and centrifugal or gravitational means. The lighter or hydrocarbon phase is withdrawn through outlet 55 having valve 56; and the heavier or hydrofluoric acid phase is recycled through conduit 71 and valve 57 to conduit 33 and to pump 15. Part or all of the light hydrocarbon material passed through conduit 55 may be returned to fractionator 32 through conduit 67 controlled by valve 68 in which case light hydrocarbons may be completely discharged through conduit 47. Such an operation is more fully disclosed, and is claimed, in my copending application Serial No. 315,063, filed March 11, 1940, now Patent 2,322,800, issued June 29, 1943.

Fractionator 37 separates the acid effluent from separator 20 into an overhead fraction comprising anhydrous hydrogen fluoride and small proportions of hydrocarbons, which is passed by way of valve 58 and conduit 59 to separator 60, and into a bottom or sludge fraction comprising fluoro-organic material, tar, etc., which is withdrawn through outlet 61 having valve 62.

In separator 60, the overhead effluent from acid fractionator 37 is separated into two phases as by cooling and centrifugal or gravitational means; a hydrocarbon phase which is withdrawn through outlet 63 having valve 64, and a concentrated hydrofluoric acid phase which is recycled by way of valve 65 and conduit 66 to pump 15. Any hydrocarbon phase may, if desired, be passed from conduit 63 through conduit 72 and valve 73 to conduit 18 and separator 20.

If desired, the sludge formed at the bottom of fractionator 37 may be subjected to thermal decomposition, whereby free hydrogen fluoride is liberated, and the resulting recovered hydrogen fluoride may be recycled to pump 15. The thermal decomposition may be effected in fractionator 37 itself, if a suitably high bottom temperature is employed, or it may be effected in a separate means, not shown.

The process of this invention is applicable to many different specific hydrocarbon feed materials, and it may be employed to produce several desirable effects. For example, in the production of isoparaffins of five to ten carbon atoms per molecule, suitable for use in aviation gasoline, fractions of straight-run gasoline or natural gasoline are suitable; these fractions may be obtained by many known means, such as fractional distillation, selective extraction, and the like. Isopentane, when reconstructed by hydrogen fluoride, yields, besides some isobutane, considerable amounts of hexanes and heptanes, mainly of rather highly branched structure, that are suitable for inclusion in aviation fuel.

A few of the many aspects of my invention are illustrated in the following examples, which are purely illustrative and not necessarily limitative of the invention.

Example I

A fraction from natural gasoline that boiled in the methylhexane range was found to have a clear ASTM octane number of 46.9 and a lead susceptibility of 11.7 octane numbers for 1 cc. of tetraethyl lead per gallon. A portion of this material was agitated with one third of its volume of concentrated hydrogen fluoride for 26 hours at an average temperature of 270° F. and under pressure sufficient to maintain all components of

the reaction mixture in the liquid phase. The reaction mixture was then cooled to 32° F. and was allowed to stand for a few minutes, whereupon two liquid phases separated out. The upper or hydrocarbon phase was equivalent to 93 per cent by weight of the original hydrocarbon charge. This hydrocarbon product was found to have approximately the following composition, in per cent by weight: propane, 1.2; isobutane, 4.1; pentane, 2.3; hexanes, 1.2; highly branched heptanes, 18.4; hydrocarbons boiling in the range of 93.5 to 100° C., 43.0, which appeared to be composed of normal heptane, isooctane, and cyclics; hydrocarbons boiling above 100° C., 11.4. This product was found to have an ASTM octane number of 54.6 and a lead susceptibility of 12.5; it contained virtually no olefinic unsaturation (by bromine titration).

Material of the character produced in this example is suitable for blending in ordinary motor fuel. Preferably, however, an aviation-gasoline cut, such as an isooctane fraction, is separated out, and part of the remainder is recycled to the treatment with hydrogen fluoride, and/or, optionally, part is used for conversion stock in other hydrocarbon-conversion processes. For example, the isobutane fraction is particularly advantageous for use in alkylation processes; the fractions boiling above the aviation-gasoline range are suitable for cracking stock to produce cracked gasoline; and the relatively low-octane fractions boiling within the gasoline range are suitable for recycling to my process.

Example II

35 A substantially pure isooctane fraction was agitated for one hour at a temperature of 70° F. with an equal volume of concentrated hydrofluoric acid. The reaction mixture was withdrawn and was separated, by settling and decanting, into an acid phase and a hydrocarbon phase. The hydrocarbon phase was equivalent by weight to 94.1 per cent of the original hydrocarbon charge. It had the following composition in mol per cent; isobutane, 29.2; pentanes, 9.1; hexanes 4.8; heptanes, 4.5; hydrocarbons boiling higher than heptanes, 52.4. The composition of the normally liquid portion of the product, in per cent by weight, was as follows: pentanes and hexanes, 15.5; heptanes, 6.8; octanes, 34.2; nonanes, 9.3; decanes, 10.9; undecanes and dodecanes, 15.0; hydrocarbons boiling higher than dodecane, 8.3.

50 This example illustrates the formation of hydrocarbons having higher and lower boiling points and correspondingly higher and lower molecular weights than those of the original material. The lower boiling compounds, particularly isobutane, are suitable for conversion stocks in alkylation processes for producing aviation gasoline; the higher-boiling compounds, such as undecanes and 55 higher, may be advantageously recycled within my process, or they may be used, for example, as conversion stock in cracking processes to produce aviation gasoline. The middle-range hydrocarbon material, such as pentanes to decanes, inclusive, is suitable for use as aviation motor fuel.

Example III

In a process for manufacturing aviation gasoline, a by-product motor-fuel-range hydrocarbon mixture is produced that has an octane number of about 63 and a tetraethyl lead response of 7.5 octane numbers for 1 cc. of tetraethyl lead per gallon. This material is treated, in accordance with the principles of my invention, with an equal volume of concentrated hydrofluoric acid. The

conditions are: temperature 350° F.; pressure, equivalent to the vapor pressure of the reaction mixture; time, 40 minutes; and rapid agitation. The reaction mixture is partly in the vapor phase. On being cooled, as to about 40 to 80° F., the resulting mixture is separated into two liquid phases. From the hydrocarbon phase, which is equivalent by weight to about 86 per cent of the original charge, is separated an aviation-gasoline fraction having an octane number of 85 and a lead response of 12.5. A relatively low-boiling fraction comprising mostly isobutane is used as feed to an alkylation process for producing aviation gasoline, and a relatively high-boiling fraction is subjected to a cracking process for producing cracked gasoline. A small proportion of tarry residue is withdrawn from the system.

Example IV

A steel bomb was almost filled with 28 grams of C. P. normal butane and 60 grams of substantially anhydrous hydrofluoric acid. Suitable means for heating the bomb, maintaining the contents in intimate mixture, and for measuring the internal temperature and the pressure were provided. The temperature was raised to 350° F., and the pressure rose to 3700 pounds per square inch. After 3 hours the heat was turned off, and the bomb was rapidly cooled. The products were withdrawn and separated by decantation. The recovered hydrocarbon layer weighed 20.3 grams; it was treated with alkaline solution to remove hydrogen fluoride. The resulting hydrocarbon product was found by fractional analysis to have the following composition, in per cent by weight:

Propane	3.2
Isobutane	4.3
Normal butane	90.0
Isopentane	2.5

100.0

Example V

In an experiment similar to that of Example IV, 64 grams of C. P. normal butane and 188 grams of substantially pure hydrofluoric acid were charged to a steel bomb having a capacity of 400 cc. During a period of two hours and twenty minutes, the temperature was gradually raised to 520° F., at which temperature the pressure was 3400 pounds per square inch. The bomb was then cooled rapidly, and the contents were removed for examination. The resulting hydrocarbon material was found by fractional analysis to have the following composition, in per cent by weight:

Methane	0.6
Propane	10.1
Isobutane	25.9
Normal butane	50.8
Isopentane	8.1
Normal pentane	2.0
Hexanes	2.0
Heptanes	0.5

100.0

The extent of isomerization of normal butane to isobutane was considerably more than that obtained in Example IV, as was also the conversion to isopentane and higher-boiling paraffins.

Approximately equal proportions by volume of isopentane and anhydrous hydrogen fluoride were charged to a steel bomb. For a period of 28 days the bomb was maintained at a temperature of 175° F. by an electric heating coil and was

shaken continuously by a mechanical rocker. The reaction mixture was then withdrawn, and a hydrocarbon phase was recovered by decanting. It was found by fractional analysis to have the following composition in per cent by liquid volume.

Lower-boiling	Trace
Butanes	8.5
Isopentane	70.2
N-Pentane	8.3
Hexanes	12.4
High boiling	0.6

15

100.0

Example VII

To a steel bomb of 400 cc. capacity were charged 84 grams of anhydrous hydrofluoric acid and 43 grams of C. P. normal pentane. The bomb was heated to 572° F. and was maintained at that temperature for 30 minutes. It was then cooled, and the products were withdrawn. It was found by fractional analysis that approximately 10 per cent of the normal pentane had reacted to give the following products in the proportions shown:

	Mol per cent
Product:	
Lower boiling	Trace
Propane	17.3
Isobutane	31.5
Normal butane	19.7
Isopentane	22.5
Hexane	6.0
Higher-boiling	3.0

40

100.0

Example VIII

To a steel bomb were charged 92.4 grams of concentrated hydrofluoric acid and 50.6 grams of normal pentane. The bomb was surrounded by an electrical heating jacket, and was heated to 570° F. in 70 minutes, as follows: up to 356° F. in 30 minutes, from 356 to 453° F. in 17 minutes, and from 453 to 570° F. in 23 minutes. At 570° F. a pressure gage attached to the bomb registered 4,240 pounds per square inch. The bomb was maintained at this temperature for 4 hours; and was then cooled to 212° F. in 14 minutes. The hydrocarbon material recovered from the bomb had the following analysis.

Lower-boiling	Trace
C ₃ H ₈	Per cent by weight 2.7
i-C ₄ H ₁₀	do 4.6
n-C ₄ H ₁₀	do 3.0
i-C ₅ H ₁₂	do 10.5
n-C ₅ H ₁₂	do 76.6
C ₆ H ₁₄	do 1.7
Higher-boiling	do 0.9

65

100.0

Example IX

To a steel bomb were charged 165.0 grams of concentrated hydrofluoric acid and 74.4 grams of normal butane, the bomb being agitated by a platform shaker. The bomb was heated from 145° F. up to 302° F. in 1 hour, and maintained at 302° F. for 2 hours. After this, the bomb was cooled to 140° F. in 15 minutes. The hydrocar-

bon material recovered had the following composition.

	Per cent by weight	10
Lower-boiling	0.0	5
i-C ₄ H ₁₀	13.4	15
n-C ₄ H ₁₀	82.4	20
C ₅ H ₁₂ (and heavier)	4.2	25
	100.0	30

It will be understood that various parts of the effluent from the process may be recycled. For example, any of the fractions obtained from fractionator 46, preferably the light-isoparaffin fraction boiling below the motor-fuel range, may be advantageously recycled to coil 13 and/or reactor 23 by means not shown that can be readily supplied by those skilled in the art; thereby the yield of hydrocarbons of a desired boiling range or of a desired carbon-skeleton structure is increased.

It also will be understood that the equipment used for this process may be of corrosion-resistant steels, Monel metal, nickel alloys, aluminum and/or magnesium alloys, copper, copper alloys, or the like. Since hydrofluoric acid is relatively inert to metals in the absence of moisture, corrosion may be minimized by using substantially completely anhydrous hydrofluoric acid and by drying the hydrocarbon material fed to the process.

My invention provides a new catalytic process for reconstructing hydrocarbon materials. It provides a new process for improving the antiknock characteristics and the degree of saturation of motor-fuel hydrocarbons. It further provides a novel process for producing hydrocarbons of higher and/or lower molecular weight than that of the original material. Still further, it provides a process wherein normal and slightly branched aliphatic hydrocarbons may be converted to relatively highly branched aliphatic hydrocarbons.

My process is especially advantageously applicable to treatment of all hydrocarbon materials which comprise predominantly saturated hydrocarbons having four or more carbon atoms per molecule. Because of the variety of materials and the plurality of purposes to which my invention is applicable, there are a large number of modifications and variations of my invention, of which only a very few are specifically described in this specification. Additional equipment such as pumps, valves, coolers, fractionators or the like, such as are well-known to those skilled in the art, may be used in my process wherever needed or convenient. It is not intended that mention herein of specific apparatus, materials, conditions, theories, reactions, or purposes should unnecessarily limit the scope of my invention.

What I claim is:

1. A process of isomerizing a normal paraffin having at least four carbon atoms per molecule, which comprises subjecting said normal paraffin to the catalytic action of 0.2 to 4 times by weight of concentrated hydrofluoric acid as the effective catalyst at an elevated temperature in the range of about 50 to 1000° F. for a time sufficient to effect a substantial extent of isomerization of said normal paraffin.

2. The process of claim 1, in which said normal paraffin is normal butane.

3. A process for improving the antiknock characteristics of a saturated hydrocarbon material boiling in the motor fuel range, which comprises subjecting such a hydrocarbon material to reac-

tion in the liquid phase while intimately mixed with 0.2 to 4 times by weight of concentrated liquid hydrofluoric acid as the effective catalyst at a reaction temperature of at least 50° F. for a time sufficient to effect alteration of the structure of saturated hydrocarbons present to form other saturated hydrocarbons, and subsequently recovering from effluents of said treatment saturated hydrocarbons boiling in the motor fuel range so produced.

4. A process of converting a saturated hydrocarbon material of at least four carbon atoms per molecule into other saturated hydrocarbons, which comprises subjecting such a material to reaction at an elevated temperature and pressure while intimately mixed with 0.2 to 4 times by weight of concentrated hydrofluoric acid as the effective catalyst for a time such as to effect a material alteration in the structure of saturated hydrocarbons in said hydrocarbon material into other saturated hydrocarbons, passing effluents of said treatment to a separating zone wherein a hydrocarbon phase is separated from a liquid hydrofluoric acid phase, subjecting said hydrocarbon phase to fractional distillation to remove residual amounts of hydrofluoric acid contained in said hydrocarbon phase, and recovering from remaining hydrocarbons a fraction containing saturated hydrocarbons of at least four carbon atoms per molecule and of altered structure so produced.

5. A process of converting a saturated hydrocarbon material of at least four carbon atoms per molecule, which comprises subjecting such a material to reaction at an elevated temperature and pressure while intimately mixed with 0.2 to 4 times by weight of concentrated hydrofluoric acid as the effective catalyst for a time such as to effect a material alteration in the structure of saturated hydrocarbons in said hydrocarbon material, passing effluents of said treatment to a separating zone wherein a hydrocarbon phase is separated from a liquid hydrofluoric acid phase, subjecting said hydrocarbon phase to fractional distillation to remove residual amounts of hydrofluoric acid contained in said hydrocarbon phase, separating low-boiling material so removed into a hydrocarbon phase and a hydrofluoric acid phase, returning said hydrofluoric acid to said reaction, returning said hydrocarbon phase to said distillation, removing as a high boiling product of said distillation a hydrocarbon material essentially free of hydrofluoric acid but containing minor amounts of organic fluorine compounds, passing said hydrocarbon material to the action of granular bauxite to remove said organic fluorine compounds and to produce a substantially fluorine-free effluent, and recovering from the hydrocarbon material so purified a normally liquid hydrocarbon fraction boiling in the motor-fuel range.

6. A process for converting hydrocarbons by reactions comprising isomerization and disproportionation, which comprises subjecting a normally liquid paraffin hydrocarbon to a reaction temperature in the presence and intimately admixed with 0.2 to 4 times by weight of liquid concentrated hydrofluoric acid as the sole catalyst for a time sufficient to convert said paraffin hydrocarbon in part to isomeric paraffin hydrocarbons of the same molecular weight and in part to paraffins of higher and of lower molecular weights.

7. A process for converting hydrocarbons by reactions comprising isomerization and dispro-

portionation, which comprises subjecting a normally liquid paraffin hydrocarbon to a reaction temperature in the presence and intimately admixed with 0.2 to 4 times by weight of liquid concentrated hydrofluoric acid as the effective catalyst for a time sufficient to convert said paraffin hydrocarbon in part to isomeric paraffin hydrocarbons of the same molecular weight and in part to paraffins of higher and of lower molecular weights.

8. A process for converting saturated hydrocarbons contained in a saturated hydrocarbon material by reactions comprising isomerization and disproportionation, which comprises subjecting a saturated hydrocarbon material to the catalytic action of 0.2 to 4 times by weight of intimately admixed liquid concentrated hydrofluoric acid as the effective catalyst at a conversion temperature for a time sufficient to effect a substantial conversion of saturated hydrocarbons contained in said material into other saturated hydrocarbons including at least one isomer of a saturated hydrocarbon so converted.

9. A process for converting saturated hydrocarbons contained in a saturated hydrocarbon material by reactions comprising isomerization and disproportionation, which comprises subjecting a saturated hydrocarbon material to a conversion temperature in the presence of 0.2 to 4 times by weight of intimately admixed concentrated liquid hydrofluoric acid as the sole catalytic material for a time sufficient to effect a conversion of saturated hydrocarbons into other saturated hydrocarbons including at least one isomer of a saturated hydrocarbon so converted.

10. A process for converting a paraffin hydrocarbon contained in a saturated hydrocarbon material, which comprises subjecting a liquid saturated hydrocarbon material containing at least one paraffin hydrocarbon of at least four carbon atoms per molecule to a conversion temperature in the presence of 0.2 to 4 times by weight of intimately admixed liquid concentrated hydrofluoric acid as the essential catalyst for a time sufficient to convert said paraffin hydrocarbon into an isomeric paraffin hydrocarbon.

11. A process for converting normal pentane into isobutane, isopentane, and isohexanes, which comprises subjecting liquid normal pentane at a conversion temperature to the catalytic action of liquid hydrogen fluoride as the essential catalyst for a time sufficient to effect a substantial conversion of normal pentane to isobutane, isopentane and isohexane, and subsequently recovering from effluents of said conversion a fraction comprising at least one of said isoparaffins so produced.

12. A process for effecting disproportionation of a paraffin hydrocarbon having at least five carbon atoms per molecule, which comprises subjecting a liquid saturated hydrocarbon material comprising such a paraffin hydrocarbon at a reaction temperature to the catalytic action of 0.2 to 4 times by weight of intimately admixed liquid hydrofluoric acid as the essential catalytic material for a time sufficient to effect a substantial disproportionation of said paraffin hydrocarbon,

forming paraffin hydrocarbons having fewer and more carbon atoms per molecule, and subsequently recovering from effluents of said reaction a fraction comprising at least one of said paraffin hydrocarbons so produced.

5 13. A process for isomerizing normal pentane to produce isopentane, which comprises subjecting normal pentane to isomerization under isomerization conditions in the presence of liquid concentrated hydrofluoric acid as the essential isomerization catalyst to form isopentane, and recovering from effluents of said isomerization isopentane so produced.

14. A process for isomerizing a saturated hydrocarbon having at least four carbon atoms per molecule, which comprises subjecting such a saturated hydrocarbon to isomerization under isomerization conditions in the presence of 0.2 to 4 times by weight of intimately admixed liquid concentrated hydrofluoric acid as the essential isomerization catalyst to form a saturated hydrocarbon isomeric with the first said saturated hydrocarbon, and recovering from effluents of said isomerization a saturated hydrocarbon fraction comprising said isomeric saturated hydrocarbon so produced.

15 15. A process of isomerizing a paraffin having at least four carbon atoms per molecule, which comprises subjecting said paraffin to the catalytic action of 0.2 to 4 times by weight of concentrated hydrofluoric acid as the effective catalyst at an elevated temperature in the range of about 50 to 1000° F. for a time sufficient to effect a substantial extent of isomerization of said paraffin.

16. A process of isomerizing a saturated hydrocarbon having at least four carbon atoms per molecule, which comprises subjecting said saturated hydrocarbon to the catalytic action of 0.2 to 4 times by weight of concentrated hydrofluoric acid as the effective catalyst at an elevated temperature in the range of about 50 to 1000° F. for a time sufficient to effect a substantial extent of isomerization of said saturated hydrocarbon.

17. A process of isomerizing a cycloparaffin hydrocarbon having at least six carbon atoms per molecule, which comprises subjecting said cycloparaffin hydrocarbon to the catalytic action of 0.2 to 4 times by weight of concentrated hydrofluoric acid as the effective catalyst at an elevated temperature in the range of about 50 to about 1000° F. for a time sufficient to effect a substantial extent of isomerization of said cycloparaffin hydrocarbon.

18. A process for isomerizing a cycloparaffin hydrocarbon having at least six carbon atoms per molecule, which comprises subjecting such a cycloparaffin hydrocarbon to isomerization under isomerization conditions in the presence of 0.2 to 4 times by weight of intimately admixed liquid concentrated hydrofluoric acid as the essential isomerization catalyst to form a cycloparaffin hydrocarbon isomeric with the first said cycloparaffin hydrocarbon, and recovering from effluents of said isomerization a hydrocarbon fraction comprising said isomeric cycloparaffin hydrocarbon so produced.
